P. G. T. DE VILLIERS

COIN SLOT

Filed Dec. 3, 1920

Inventor.

Peter G. T. de Villiers.

by Parker & Carter
Attorneys.

UNITED STATES PATENT OFFICE.

PETER GYSBERT THOMAS DE VILLIERS, OF PRETORIA, TRANSVAAL, SOUTH AFRICA,
ASSIGNOR OF ONE HALF TO ARTHUR ROGERS-JENKINS, OF DURBAN, NATAL, UNION
OF SOUTH AFRICA.

COIN SLOT.

Application filed December 3, 1920. Serial No. 427,951.

To all whom it may concern:

Be it known that PETER GYSBERT THOMAS DE VILLIERS, a British subject, residing at Department of Posts and Telegraphs, General Post Office, Pretoria, Transvaal Province, of the Union of South Africa, has invented certain new and useful Improvements Relating to Coin Slots, of which the following is a specification.

10 The present invention has reference to coin-in-the-slot machines, in which provision is made for insertion of coins of different denominations, e. g., certain types of telephone call boxes.

15 The purpose of the invention is to prevent the simultaneous insertion of coins of different denominations; and a further purpose is to facilitate the insertion of coins in the slots.

20 The invention is illustrated in the accompanying drawings, in which—

Fig. I is a perspective view of the upper portion of a telephone payment box and

Fig. II is a detached view of the runway and slot locking plates hereafter described.

25 Figs. III, IV and V are vertical sections through the slots showing the different positions of the locking plates.

Referring to the drawings, 1 indicates the upper wall of the cover of a telephone payment box in which are formed the slots 2, 3, 4 of progressively increasing size, to receive, for instance, three-penny pieces, six-penny pieces and shillings. Secured to the 30 wall 1 is a casting 5, open above the slots 2, 3, 4 and providing behind said slots tablets 6 on which the values of the different denominations are imprinted. In front of each slot the casting is formed with a channel 7 which is flared at the front and provides a means for readily guiding the coin into the slot, the coin being simply slid, on edge, along the surface 1 towards the proper slot when the channel 7 guides the same accurately into the slot; the tablets 6 forming stops to prevent coins from passing beyond the slots.

40 In a telephone payment box it is usual for the insertion of the coin or coins to be signalled to the exchange, and for this reason it is desirable to prevent more than one coin being inserted at a time. To ensure this there is arranged beneath the slots 2, 3, 4 a

runway 8 in which plates 9, 9^a are free to slide in the line of the slots. The outward movement of said plates is limited by stops 10 and they are provided with projecting arms 11 by which they make contact with one another. Said plates 9, 9^a partially blind the slots, to the extent of providing passage room for only one coin at a time. As shown in Fig. III, assuming that the smallest slot 2 is fully uncovered for the insertion of a coin, then the plate 9 is pushed over to cover the right hand end of the slot 3, and it also pushes over the plate 9^a so as partly to cover the right hand end of slot 4. Again as shown in Fig. IV, the centre slot can only be fully open when the plates 9, 9^a are moved fully to the right and left, so that the former covers the left hand end of slot 2, whilst the latter covers the right hand end of slot 4. To enable a coin to be inserted in slot 4, both plates 9, 9^a must be pushed over to the right as indicated in Fig. V, whereby the left hand ends of slots 2 and 3 are covered. The extent to which the plates overlap the slots is so limited that the insertion of a coin into any slot which is partially closed by its plate or plates 9, 9^a, readily thrusts the latter out of the way of the coin provided the other slots are free.

I claim:

1. Coin-in-the-slot apparatus having several slots adapted to receive coins of different denominations comprising a series of plates slidably mounted end to end beneath the slots, the plates being of such a length that the insertion of a coin in one slot alters the relative positions of the plates so that the other slots are partially closed, means being provided whereby no slot can be completely closed.

2. Coin-in-the-slot apparatus having several slots adapted to receive coins of different denominations comprising a runway adapted to carry slidably, a series of plates having projecting arms whereby they make contact with one another endways, said arms being at all times clear of the slots, the plates and arms being of such a length that the insertion of a coin in one slot moves the plates so that the other slots are only partially closed.

In testimony whereof I affix my signature.

PETER GYSBERT THOMAS de VILLIERS.
